UNITED STATES PATENT OFFICE.

ALWYNE MEADE, OF BLACKHEATH, ENGLAND.

FURNACE-GRAVE.

1,333,812.

Specification of Letters Patent. Patented Mar. 16, 1920.

Application filed April 25, 1919. Serial No. 292,585.

To all whom it may concern:

Be it known that I, ALWYNE MEADE, a subject of the King of Great Britain and Ireland, and a resident of Blackheath, county of Kent, England, have invented a certain new and useful Improvement in Furnace-Grates, of which the following is a specification.

This invention, which relates to improvements in furnaces and grates therefor, is especially applicable to the type of furnace commonly employed in conjunction with gas-works' retort settings, but is also applicable to furnaces of any kind in which solid fuel is used.

The object of my invention is to construct a furnace with a grate which cannot be displaced during the operation of raking the fire, while any one of the hanger-bars may, if and when necessary, be removed by a slight forward movement, and which shall, by the introduction under the fuel bed, of air injected by means of a jet of high or low pressure steam, be kept cool without the necessity for any system of water cooling.

A further advantage of my invention is that the construction of the grate combined with the injection of air reduces the formation of clinker, and with some fuels low in ash content, practically avoids its formation altogether.

In the ordinary form of step grate the fuel is supported by a series of flat plates each one of which is placed slightly in advance of the one above it. In my improved grate, specially designed cast-iron hanger-bars are employed instead of the flat plates, and these hanger-bars are suspended from special cross-bars so as to form a grille upon which the fuel rests. The cross-bars are so designed that the hanger-bars are maintained in the correct position to afford the requisite amount of grate area. These cross-bars are cast with parts which are alternately triangular and circular in cross-section, so as to be reversible and are provided with square extremities which have beveled top edges and which rest in cast iron supporting boxes built into the walls of the furnace.

The boxes are made right and left hand and tapered from front to back, having in addition two upstanding lugs on the top so that the boxes can be securely built into the furnace walls with the narrow end to the outside. The recesses in the boxes for the

cross-bars are deeper at one side to enable the cross bars to be inserted after the boxes are built in. The cross bars are then pulled toward the front of the furnace and dropped into their final position in the boxes, a vertical step in each box preventing the cross-bar from leaving its position until its removal is required.

Referring to the accompanying drawings:

Figure 1 is a vertical sectional view of a furnace embodying the present improvements.

Fig. 2 is a half-front view of the grate, and

Fig. 3 is a vertical sectional view illustrating the manner of suspending the hanger bars from the cross-bars.

Fig. 4 is a perspective view of part of a cross-bar showing the square ends, with beveled top edges and alternate triangular and circular portions.

Fig. 5 is an elevation, and

Fig. 6 a plan partly in section of a box for supporting the ends of the cross bars.

Fig. 7 is an elevation, partly in section, of the injector with Venturi pipe and steam connections, and

Fig. 8 is a plane of the Venturi pipe showing the long radius bend and mouthpiece.

The hanger-bars *a* are constructed from hard cast-iron and are of S shape. The upper portion *a'* forms a hook (strengthened by two webs *a*²) by means of which the bar *b* is suspended from the cross bars *b*. The central portion of the hanger-bars is of convex shape in order that the fuel resting on the grate may be held away from the point of attachment of the hook-end *a'*. The lower end *a*³ of the hanger-bar is made broader than the central portion and provided with a web *a*⁴ for additional strength and is bent around, and this end wrapping around the triangular portion of the cross-bar *b*, effects a locking action which prevents the hanger-bars from becoming disengaged during the process of cleaning the fuel bed. On the back of the hanger-bars is cast a web *a*⁵, provided with two holes into which a Y-shaped bar may be inserted for the purpose of removing the hanger-bar when necessary.

The cross-bars *b* having the alternate round and triangular portions *b'* and *b*² respectively, and also the beveled upper edges *b*³ on the box ends perform a double func-

tion in that (as the triangular portions protrude beyond the circular portions upon which the hanger-bars are suspended) each hanger-bar is maintained in its correct position, while the lower end of the hanger-bar engages with the base of the triangular portion of the supporting bar underneath and thus effects the locking action hereinbefore referred to. At the same time, while the hanger-bars *a* are locked while in their working position, each one may at any time be unhooked and removed with the aid of the Y-shaped bar by disengaging its lower end from the triangular portion of the cross-bar by applying to such lower end a slightly forward movement.

In Figs. 5 and 6 (Sheet 2) is shown a cast-iron box *c* designed for the left-hand side of the furnace. *C'* is a step for keeping the cross-bar *b* in its position in the recess *c²*. The deeper recess *c³* temporarily accommodates the end of the cross-bar when being put into position, and the inclined intermediate wall *c⁴* between the recesses serves 25 to guide the bar into position when the beveled edge *b²* thereof engages with the said wall.

The introduction into the furnace of the primary air required for the combustion of the fuel is effected by means of two injectors, one on each side of the furnace door 30 built into the wall and discharging under the fuel bed, and using steam at any convenient pressure (according to the adjustment of the injectors) but preferably about 35 10 lbs. per square inch.

Each injector consists of a cast-iron Venturi-pipe *d* with a long radius bend passing through the brickwork ending in a mouth-piece *d'* directed rearward under the fuel bed and with a lip projecting clear of the brickwork.

The inlet of the Venturi pipe is partially closed by a flange *d²* screwed on to a nipple 45 in a T-piece *d³*. A similar cored hole is provided on the bottom of the Venturi pipe so that the latter can be used on either side of the furnace door, the cored hole not required being plugged off.

The flange *d²* is adjustable on the screw nipple, the outer end of which is closed with a screw cap, and can be locked with a lock nut so as to leave any desired gap all around the edge of the flange for admitting 55 air into the Venturi pipe and around the

T-piece. The outlet of the T-piece is finished with a tapered nipple from which the steam is directed forward along the Venturi pipe inducing a current of air which mingles with the steam and is injected into the furnace.

Having now described the nature of my invention, what I claim as new and desire to secure by Letters Patent of the United States is:—

1. In a furnace of the class described, a grate including cross bars arranged one above the other and formed with alternate round and triangular portions, and hanger bars having hook portions for engaging with the rounded portions of one bar and relatively angular portions for engaging with the triangular portion of the bar below.

2. In a furnace of the class described, a grate comprising cross bars having rectangular end portions provided with opposite upper beveled edges, hanger bars adapted to engage with the cross bars, boxes for receiving the rectangular ends of the cross bars and each including a chamber for initially receiving the end of the bar and a chamber for holding the bar in locked position and each of said boxes being provided with a stepped shoulder between the bottoms of the chambers and with an inclined guide wall connecting the tops of said chambers.

3. In a furnace of the class described, the combination with the furnace walls of bar receiving boxes held in said walls and each having an intermediate shoulder portion, cross bars having rectangular end portions for fitting in the boxes and being held in position by the respective shoulders, and hanger bars connecting the cross bars.

4. In a furnace of the class described, a grate consisting of a plurality of cross bars arranged at different levels and in an inclined plane, hanger bars supported by the cross bars and each consisting of a body having a relatively round hook portion at one end for engaging with the rear side of one of the cross bars and having a relatively angular portion at its other end for engaging with the opposite side of a lower bar, and means carried by the back of said hanger bars for receiving a withdrawing hook.

In testimony wherof I have affixed my signature this first day of April, 1919.

ALWYNE MEADE.
